UNITED STATES PATENT OFFICE.

GEORGE W. LEWIS, OF PORTSMOUTH, VIRGINIA

JOURNAL-BOX.

946,237.

Specification of Letters Patent. Patented Jan. 11, 1910.

Application filed January 29, 1909. Serial No. 475,046.

To all whom it may concern:

Be it known that I, GEORGE W. LEWIS, a citizen of the United States, residing at Portsmouth, in the county of Norfolk and 5 State of Virginia, have invented a certain new and useful Improvement in Journal-Boxes, of which the following is a full, clear, and exact description.

The object of this invention is to provide a journal box or axle-box for use on railway car trucks, wherein an economical distribution of the oil in the waste-receiving space is made, and whereby the journal may be properly lubricated with a very small 15 quantity of waste.

The invention consists of a journal-box, the upper portion of which is or may be of any ordinary or approved construction, and the lower portion of which is made with a 20 V bottom for a length not less than the length of the journal, and provided with oil and waste-receiving cavities at front and rear, all as I will proceed now more particularly to set forth and finally to claim.

25 In the accompanying drawings, illustrating the invention, in the several figures of which like parts are similarly designated, Figure 1 is a side elevation of a journal-box embodying the improvements. Fig. 2 is a 30 longitudinal central section thereof. Fig. 3 is a horizontal section taken substantially in the plane of line A, Fig. 2, and looking toward the bottom of the box. Fig. 4 is a transverse section taken substantially in the 35 plane of line B, Fig. 2. Fig. 5 is a rear end elevation.

The upper portion of the box with the necessary provisions for the reception of the arch-bar, the key and brass, and the 40 dust-guard where desired, and the bolt receptacles, may be of any usual or approved construction, and are herein so shown. The mouth may have outwardly beveled lips to coöperate with a complementary lid, but these 45 features are the invention of another, and are not herein claimed.

The bottom of the box is of an essential novel construction, as I will proceed now to describe.

50 The fore part 1 of the bottom affords a cavity for the reception of waste and lubricant, and just back of this fore part the sides of the box are slanted inwardly and rearwardly so as to make the doubly-inclined walls 2, and these doubly-inclined walls are continued rearwardly in the V shaped bot-

tom walls 3 which meet at the bottom of the box and substantially in the plane of the axis of the journal, so as to provide a V shaped trough, as it were, beneath the axle 60 journal 4, shown in dotted lines in Fig. 2, and thereby permit the box to be packed with waste not only beneath the journal, but about its sides; the double incline of the walls 2 admitting of the insertion of the 65 waste back of the button of the journal in the most efficient manner and in a very easy way. At the extreme rear of the box the V shaped bottom takes a dip, as at 5, which forms an internal cavity 6 extending across 70 the apex of the V and part way up each side, as indicated by the full lines in Figs. 1, 2 and 3 and by the dotted lines in Figs. 4 and 5. This cavity 6 affords a receptacle for waste so that the axle may be packed 75 around its collar, and thus the necessity for a dust-guard largely obviated. Where a dust-guard is not intended to be employed, the dust-guard pocket 7 may be omitted. Where the dust-guard is employed, its lower 80 end will be shaped to conform substantially to the shape of the rear end of the box.

This box is designed to conform to Master Car Builders' standards, and it is substantially so shown in the drawings. 85

In my Patent No. 896,998, dated August 25, 1908, I have shown and described a journal-box with a V shaped bottom, and a front oil and waste-receiving chamber, and the advantages of the invention set forth in said 90 patent apply with equal force to the invention of this present case, and in addition the present invention by its provision of the doubly-inclined walls at the front of the V bottom permits the freer and fuller packing 95 of the journal with waste, and the provision of the internal cavity at the rear enables me to lubricate and pack the journal about its collar and practically to dispense with the dust-guard. 100

As indicated more particularly in Fig. 3, the doubly-inclined walls 2 do not have distinctly marked lines of separation from the bottom of the front oil and waste receptacle 1, and from the sides of the box, and from 105 the walls of the V shaped bottom, but, on the contrary, the walls 2 join these parts by vanishing into them.

What I claim is:

1. A journal-box, having its lower portion provided with a front oil and waste receptacle which merges in a V shaped bottom 110

arranged below the place where the journal would extend in use, said receptacle and the front of the said V shaped bottom connected by doubly-inclined walls.

5 2. A journal-box, having its lower portion provided with a front oil and waste receptacle, and a V shaped bottom extending from said front oil and waste receptacle rearwardly, and walls connecting said receptacle and bottom inclined inwardly and rearwardly to provide for the efficient and easy packing of the nib of the journal.

3. A journal-box, having its lower portion provided with a front oil and waste receptacle which merges in a V shaped bottom arranged below the place where the journal would extend in use, the front of the said V shaped bottom having doubly-inclined walls, and its rear having a V shaped dip 20 which furnishes an internal waste-receiving cavity.

4. A journal-box, having an oil and waste receptacle at the front of its lower portion,

and next adjacent thereto a V shaped bottom connected with the receptacle by walls slanting inwardly and rearwardly, said V shaped bottom terminating at the rear in a transverse V shaped cavity extending below said bottom.

5. A journal-box, having an oil and waste 30 receptacle at the front of its lower portion, and next adjacent thereto a V shaped bottom connected with the receptacle by walls slanting inwardly and rearwardly, said V shaped bottom terminating at the rear in 35 a transverse V shaped cavity extending below said bottom and up into the sides and adapted to receive waste for packing around the collar of the journal.

In testimony whereof I have hereunto set 40 my hand this 21st day of January A. D. 1909.

GEORGE W. LEWIS.
